UNITED STATES PATENT OFFICE

WINFIELD S. GRANT, OF DETROIT, MICHIGAN, ASSIGNOR TO HENRY D. MACKAYE,
DETROIT, MICHIGAN

OIL BURNER

Original application filed December 5, 1927, Serial No. 237,947. Divided and this application filed August 20, 1928, Serial No. 300,772.

This invention relates to oil burners for various types of furnaces or heating apparatus, the principal object being the provision of a new and novel oil burner and particularly a fire pot used in connection therewith, and is a division of my application for Letters Patent of the United States for improvements in oil burners filed December 5, 1927 and serially numbered 237,947.

10 Another object is the provision of a new and novel oil burner pot for oil burning apparatus so designed and constructed as to preclude the passage of unvaporized fuel particles out of the same into the combustion chamber of the boiler or other apparatus for which the heat is being provided, and so formed as to provide without any mechanical aid of any description a relatively flat and wide spread flame.

20 Another object is the provision of a burner apparatus for oil burning mechanisms so designed and constructed as not to depend upon an excess of air supplied to the same for the complete vaporization of the oil being burned.

25 A further object is the provision of a fire pot for oil burning mechanism in which a refractory lining is provided and so mounted with respect to the shell of the fire pot as to be quickly brought to an incandescent condition 30 and maintained in such condition for a relatively long time after discontinuance of a heating medium, by the prevention of heat transfer therefrom through its shell.

35 The above being among the objects of the present invention, the same consists in certain features of construction and combinations of parts to be hereinafter described with reference to the accompanying drawings, and 40 then claimed, having the above and other objects in view.

In the accompanying drawings which illustrate a suitable embodiment of the present invention and in which like numerals refer to 45 like parts throughout the several different views,—

Fig. 1 is a plan view of the oil burning apparatus the furnace being shown in the horizontal section.

50 Fig. 2 is a side elevation of Fig. 1 partially

in section, the muffler being removed to better illustrate the construction of the same.

Fig. 3 is an enlarged vertical sectional view taken on line 3—3 of Fig. 1, longitudinally through the oil burner nozzle and centrally 55 through the fire pot.

Fig. 4 is a vertical sectional view taken on the line 4—4 of Fig. 1 and illustrates the form of flame obtained by the use of the fire pot illustrated.

In the drawings is shown a conventional type of furnace 15 which may be especially designed for use in connection with the present invention or may be of the usual coal burning type which has been converted into an oil burning type by the use of the present invention. Within the ash pit 16 of the furnace is a fire pot designated generally in Figs. 1 and 2 as 17, which is supported from the floor of the ash pit by the standard 18 which adjustably engages the apertured boss 19 formed on the outer surface of the fire pot 17, the fire pot 17, being locked in vertical adjusted position by means of the set screw 20. Integral with the fire pot 17 is the nozzle or venturi 21 which enters the fire pot at a tangent to the interior surface thereof. Supported exteriorly of the furnace on the legs 22 is the stand 23 which supports the electric motor 24. On one end of the motor 24 is secured a fan or blower 25 which may be of any conventional type, but for the purpose of illustration is shown as a centrifugal type of blower, it being provided with a discharge passage 26 which extends through the door 27 of the ash pit 16 and is socketed in the outer end of the venturi 21. The air intake for the fan 25 extends axially from the fan casing on the side thereof opposite the motor 24 and receives at its free end a muffler or silencer 29. This serves to muffle the sound of the air rushing through the fan and its passages and also serves to muffle the noise of combustion of the gases in the fire pot 17 which tends to travel back through the passage 26 and out through the fan 25.

The oil is conducted through the pipe 42 to a valve mechanism having a casing 43 and then through the pipe 44 to another 48

valve mechanism having a casing 45. From the casing 45 the oil is conducted through the pipe 46 to a third valve mechanism, the casing of which is indicated as 47, and thence 5 through the pipe 48 into the interior of the fan passage 26, the pipe 48 terminating in the nozzle end 49 which is provided with a plurality of radial openings 50 for the escape of the oil. The purpose of the foregoing 10 valves which are inserted in the oil line will be described later.

As set forth in the objects of the present invention, the construction herein disclosed employs no pilot light, the fire never being 15 extinguished, but instead, being merely checked when the room or other space being heated has reached a desired maximum temperature, the mechanism being constructed to provide a high and low fire. It is obvious 20 that in attaining such a result the air and the fuel being fed to the mechanism will at no time be completely shut off, but that in changing from high to low fire a lesser amount of air and oil will necessarily have 25 to be fed to the mechanism than for high fire conditions. My method of controlling the air is to provide the fan 25 of such capacity that at full speed of the motor 24 the desired amount of air for high fire conditions 30 is being fed to the burner, and I prefer to allow the motor 24 to run at a constant speed and to reduce the amount of air being passed by the same to the burner for low fire conditions by throttling the amount of air which 35 the fan 25 may draw into the same. I accomplish this result by positioning a butterfly valve 51 on the shaft 52 within the intake passage 28 of the fan 25 and securing to the upper end of the shaft 52 above the passage 40 28 a lever 53. Rotatably secured to the shaft 52 above the lever 53 is a second lever member 54 provided with a slot 55 as indicated in Fig. 1. The screw 56 projects downwardly through the slot 55 and threadedly engages 45 the lever 53 and thereby locks the levers 53 and 54 together for equal rotational movement, the rotational position of the lever 54 with respect to the lever 53 being adjusted by loosening the screw 56 and moving the lever 50 54 within the limits of the slot 55, this adjustment allowing the butterfly valve 51 to be adjusted for high fire or maximum volume of air passing through the fan 25. On the lower end of the shaft 52 below the casing 55 28 I provide a third lever 57 secured thereto, the free end of the lever being provided with a screw 58 which is adapted to bear against the boss 59 formed on the lower surface of the casing 28 to control the low fire or minimum volume of air being passed through the fan 25, the screw 58 being threaded inwardly or outwardly to regulate the position of the butterfly valve 51 for this condition and thus determining the amount of space 60 85 between the edges of the butterfly valve 51

and the casing 28 through which air may pass to the fan 25 at low fire position. The lever 54 is connected by the link 60 to the core or armature 61 of a suitable solenoid 62 which is automatically actuated as described later, in order to move the butterfly valve from low fire to high fire position.

The oil from the pipe 42 enters the interior of the casing 43 and passes out of the same into the pipe 44. A needle valve 65 provided with a suitable indicating and controlling head 66 cooperates with the valve 63 to limit the amount of oil which may flow through the opening 63 under the constant head provided for by the supply reservoir, this serving to regulate the amount of fuel flowing to the burner for high fire conditions when the maximum amount of oil is being used. A suitable pointer 67 is preferably provided in conjunction with the control head 66 for visual location of the needle valve 65 with respect to the opening 63. The oil from the pipe 44 flows through the solenoid controlled valve 45 which is connected in series with the solenoid valve 62 for the 90 air supply fan and the supply of current to both of which is controlled by one or more suitable thermostats (not shown) located in the room or rooms heated by the furnace, as will be readily understood. The valve member 45 is so constructed that when the main flow of oil through the same for high fire conditions is shut off upon operation of the solenoid, sufficient oil is by-passed past the valve to the pipe 46 to take care of low fire 95 conditions, as is fully explained in my previous patent application above referred to.

As this far described, the mechanism for providing a maximum and minimum amount of oil and air has been explained, it being understood of course, that the solenoids 73 and 62 are so controlled as to furnish a maximum amount of air for the maximum amount of oil and vice versa. The construction of the fire pot and burner nozzle and 100 venturi will now be described.

As shown best in Figs. 3 and 4, the fire pot comprises a cup-shaped metal part or portion 76 and a refractory lining 77 conforming in shape to the portion 76, the refractory lining 77 being formed at the upper edge thereof to provide an inwardly extending annular flange portion 78 which I prefer to term a diaphragm. What may be termed a "dished" upper surface of the diaphragm 78 is shown as formed complementary to a substantially spherical surface and as receding from a thin inner edge thereof in an upwardly curved manner,—the bottom of this flange being shown as flat and as disposed in substantially the same plane as a circular upper edge of cup 76. I prefer to so form a cylindrical wall and bottom wall of the lining 77 with respect to the corresponding walls of the cup 76, that when these two 110 115 120 125 130

parts are in cooperative relationship a dead air space such as 79 is formed between the adjacent walls of the same, this being an important feature as will be later described. As previously described, the fire nozzle or venturi is formed integral with the portion 76 of the fire pot and extends into the interior thereof in a direction tangential to the interior side face of the refractory material 77, the nozzle being modified in cross section 10 from a circle at its rear end to an ellipse at the discharge end within the fire pot in order to impart greater velocity to the gas being ejected from the same into the fire pot. Formed in the bottom wall of the fire nozzle, 15 as shown in Fig. 3, is what may be termed a well or receptacle 79 provided with a baffle 80 extending upwardly and inwardly from the bottom interior wall of the nozzle 21 at the rear end of the well 79 over the rear portion 20 thereof, thus forming a hood over such portion. This baffle or hood 80 is provided with a plurality of openings 80' through the same for the purpose of conducting a metered amount of air through the baffle for a 25 purpose to be described later. The metal along the edges of the well 79 is formed to provide inwardly extending flange portions 81, and received within the well 79 under the 30 flanges 81 is an absorbent pad 82 which may be formed of suitable fibrous asbestos material, or other suitable material, and a screen such as 83 is provided over the upper surface of the pad 82 for maintaining the same 35 in place and providing a ready passage for oil to the pad and the gases vaporized off of the pad 82 into the nozzle. As indicated in Fig. 3, the oil nozzle 49 is positioned substantially in line with the inner edge of the 40 baffle 80 so that the oil being discharged from the same through the openings 50 will fall upon the pad 82. The design of the nozzle and fire pot is such that in operation the oil from the nozzle 50 is deposited upon 45 the pad 82 which absorbs the same, the heat from the fire pot is conducted back through the fire nozzle 21 and heats the pad 82 to a relatively high degree which causes the oil absorbed thereby to be given off in the form 50 of a vapor which is picked up by the air from the fan 25 and is carried into the fire pot.

In operation the fire actually extends over the pad 82 and in low fire operation all of the oil that enters the fire pot is in the form of 55 vaporized gas coming solely from the pad 82. During high fire operation when the maximum blast of air from the fan 22 is passed through the fire nozzle 21, a certain amount of unvaporized oil particles in the 60 form of a mist may be carried directly into the fire pot without having had the opportunity of being deposited upon the pad 82 and absorbed thereby to be later heated and vaporized into the form of a readily combustible gas. Inasmuch as the pad 82 is of

a relatively substantial area, the baffle 80 is provided at the rear of the same in order to deflect the bulk of the air upwardly over the pad. The openings 80' are provided in the baffle 80 so that during low fire operation sufficient, and substantially only sufficient, air will pass through the openings 80' to form with the gas being given off from the pad 82 a perfect combustible mixture which will burn with a clear flame and produce no 70 smoke. The combined area of the openings 80' for this purpose is best determined by actual experience rather than calculations. At the same time, the baffle 80 protects the pad 82 from any sudden blasts of air such as may occur when the butterfly valve 51 is 75 suddenly opened, and thus prevents possible blowing out of the flame above it. The pad 82 in this construction not only serves the purpose of the pilot light used in the conventional oil burner system but in addition serves as the sole means of supplying oil in a vaporized state to the fire pot, it being such as to positively preclude its being extinguished by any blast of air from the fan 25, 80 and such as to provide a sufficient fuel reserve therein for continuous combustion for a substantial period of time, for instance, fifteen minutes to one-half hour, depending upon the size and surface area of the pad 82, 85 after the flow of oil through the nozzle 49 has completely stopped. The flange projected into the fire pot through the nozzle 21, and the combustible mixture which is carried thereby and has its combustion completed within the fire pot, because of the tangential direction in which it is introduced into the fire pot, is caused to swirl around the same and gradually rises upwardly into contact with the diaphragm 78 and then is 90 forced upwardly through the central opening of the same. The flame and gases in passing upwardly through the diaphragm 78 form a low pressure area directly over the diaphragm 78 which acts to pull the flame 95 outwardly and imparts to the same a flat mushroom type of swirl formation as indicated in Fig. 4. This flame which may be 100 regulated by proper adjustment of the butterfly valve 52 and needle valve 65, may be 105 controlled so as to approach close to but out of contact with the said walls of the furnace 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 10230 10235 10240 10245 10250 10255

will be readily recognized, and it will be further readily understood that in obtaining this form of flame I am enabled to obtain a stack temperature of as low as 200° F. as opposed to a stack temperature of between 600° and 700° F. obtained in the usual oil burning mechanism, the saving of heat as a result of this feature being enormous.

Under high fire conditions when the maximum amount of oil and air is being fed to the fire pot, a certain amount of oil from the nozzle 49, as previously described, may be carried into the fire pot in the form of a mist of unvaporized fuel particles such as the conventional constructions depend upon entirely for combustion. In such a case, these particles being heavier than the bulk of the combustible mixture being fed into the fire pot, and because of the rotary motion imparted to the mixture by the formation and location of the fire nozzle 21, the centrifugal force acting on the particles will throw them outwardly into contact with the incandescent refractory lining 77 which will quickly vaporize the same and they will thereafter be discharged through the diaphragm 78 in the form of a vaporized gas. The diaphragm 78 serves to prevent any of these unvaporized fuel particles from being carried above the fire pot inasmuch as the centrifugal force acting on the particles confines the path of the particles to a point in the fire pot axially outwardly from the inner edge of the diaphragm 78. In forming the refractory lining 77 with the airspace 79 between the same and the metallic cup portion 76 I am enabled to heat the refractory material 77 to a substantially higher temperature and degree of incandescence than in the conventional constructions, inasmuch as the air space 79 serves as an insulation between the refractory material 77 and the cup 76 and thereby cuts down the conduction and radiation of heat from the cup portion 76 to a minimum. It also serves as a means for allowing the refractory material 77 to be brought to a point of incandescence in a much shorter period of time than in conventional constructions, and further serves to hold it at such temperature for a relatively greater period of time after the flame within the fire pot has been extinguished.

In accordance with the laws of some States, means must be provided in apparatus of this type such that should oil in liquid form accumulate within the fire pot the flow of oil to such pot will be stopped, this being a safety provision for eliminating possibility of an explosion due to the accumulation of a material body of oil. This provision is taken care of in the present invention by forming an upwardly projecting boss 84 on the floor of the cup portion 76 of the fire pot and of such a height as to extend into flush relationship with the floor of the insulating material 77.

The boss 84 is shown as tapered favorably to a sealing fit and as provided with a central opening 84' the lower end of which is screw-threaded for connection with the pipe 85 as indicated in Fig. 3. The pipe 85 in turn extends forwardly out through the door 27 of the ash pit 16 and terminates above the bucket 86 which is suspended from the free end of the lever 87 which actuates the trip valve 47. In operation, should for some reason or other an excess of liquid oil accumulate in the fire pot, the oil will pass down through the opening 84' into the pipe 85 and be drained into the bucket 86. The valve 47 is so arranged that when a predetermined weight of oil is drained into the bucket 86, the weight of the oil and bucket acting through the arm 87 will actuate the valve 47 to stop the flow of oil to the burner.

A safety feature best shown in Fig. 3 comprises a thermostatic switch inserted in the electrical connections leading to the solenoids 62 and 73. This switch comprises the insulated base 104, the contact member 105, and the strip of thermostatic metal 106 supported at one end on the binding post 107 within the fire nozzle 21 and adjacent the open end of the same. The electrical current passing through the solenoids 62 and 73 is adapted to pass between the binding posts 105 and 107 through the thermostatic strip 106 which is so formed that when cold or relatively cold its free end is bent outwardly out of contact with the binding post 105 and when heated straightens out and makes contact with the binding post 105 and thereby permits the passage of electricity between the posts 105 and 107. Under normal operation of the burner sufficient heat is supplied to the thermostatic strip from the gases burning above the pad 82 to insure contact of the thermostatic strip 106 with the binding post 105, but if for any reason all flame should become extinguished within the fire pot of the fire nozzle 21, the strip 106 will bend away from the binding post 105 and thereby interrupt the flow of electricity to the solenoids 62 and 73 and move the mechanism to low fire position.

The novel form of fire pot which I have provided serves to produce a flame within the furnace which much more economically contacts with the heating surface of the furnace than in the conventional constructions and this without the employment of any mechanical spreading means of any description whatsoever and, further, that complete burning of all the oil particles is assured and the formation of carbon prevented.

Although I have shown in the accompanying drawings and described a variety of separate and distinct features which I have combined to form an oil burner of novel construction and distinct formation it will be recognized, of course, that various of these

devices may be eliminated under certain conditions or may be employed in connection with devices of a different type, and I do not limit myself to the employment of the same to the specific assemblage with parts and to the exact construction shown and described, but desire to state that formal changes may be made in the specific embodiment of the invention described without departing from the spirit or substance of the broad invention, the scope of which is commensurate with the appended claims.

What I claim is:

1. A fire pot for oil burning apparatus having a tangential inlet and comprising a cup-shaped member provided with a substantially cylindrical wall and with an inwardly extending flange adjacent an open upper end thereof, the lower surface of said flange being substantially flat, the upper surface of said flange being curved outwardly and upwardly, and said flange being thinnest at its inner edge.

2. A fire pot for oil burning apparatus comprising a cup-shaped member provided with an inlet disposed to impart a whirling movement to a mixture admitted therethrough and with an inwardly extending flange adjacent the open end thereof, the upper surface of said flange being dished to form a low pressure area over said flange and said flange being thinnest at its inner edge, whereby to spread the flame passing upwardly therethrough.

3. A fire pot for oil burning apparatus comprising a cup-shaped member having an inwardly extending integral annular flange adjacent the open end thereof, the outer face of said flange being formed complementary to a part of an approximately spherical surface and the inner face of said flange being substantially flat, and means for introducing a combustible mixture into said member in a direction tangential thereto and below said flange.

4. A fire pot for oil burning apparatus comprising a cup-shaped member provided with an inwardly extending integral annular flange adjacent the open end thereof, the surface of said flange most remote from the bottom of said cup being concave and curved outwardly and away from said bottom, and the surface of said flange more adjacent to said bottom being substantially flat and disposed in a plane substantially perpendicular to the axis of said cup; and means for imparting a whirling motion to a fuel mixture upwardly advancing past said flange.

5. A fire pot for oil burning apparatus comprising a cup-shaped member provided with an inwardly extending integral annular flange adjacent the open end thereof, the surface of said flange most remote from the bottom of said cup being concave and curved outwardly and away from said bottom, the

surface of said flange more adjacent to said bottom being disposed in a plane substantially perpendicular to the axis of said cup, and means for introducing a combustible mixture into said cup below said flange in a direction tangential to the interior surface of said cup.

6. A fire pot for oil burning apparatus comprising, in combination, a metal cup having a tapered nozzle member integral therewith and disposed to discharge into said cup, and a refractory lining for said cup spaced from the sides thereof, the space between said cup and lining being sealed at the open edge of said cup and about said nozzle against the circulation of air.

WINFIELD S. GRANT.
